[57] CLAIM

The ornamental design for a hollow inflatable bell for pulling by a power boat tow rope, as shown and described.

DESCRIPTION

FIG. 1 is a top plan view of a hollow inflatable bell for pulling by a power boat tow rope showing our new design; FIG. 2 is a large end elevational view thereof; FIG. 3 is a small end elevational view thereof; and, FIG. 4 is a top isometric view thereof with the handle rotated 90° from the handle in FIG. 1.

The drawings depict the bell of this design in clear plastic and the air chambers are interconnected to permit inflation through a single valve.
